UNITED STATES PATENT OFFICE.

GEORGE LAWSON BALLARD, OF NORRISTOWN, PENNSYLVANIA, ASSIGNOR TO WILD-MAN MFG. CO., OF NORRISTOWN, PENNSYLVANIA, A CORPORATION OF PENNSYLVANIA.

KNITTED FABRIC AND METHOD OF MAKING THE SAME.

Original application filed November 6, 1922, Serial No. 599,402. Divided and this application filed November 6, 1924. Serial No. 748,180.

This specification is a division of that filed by me Nov. 6, 1922, Serial Number 599,402, now Patent #1,608,194, and concerns the product i. e. the stocking made on the machine of said application.

In the accompanying drawings

Figure 1 is a view of a portion of the split fabric which appears in the stocking in the foot and above the heel.

10 Fig. 2 is a diagrammatic view of the stocking.

Fig. 3 is a diagrammatic perspective view of the needles and associated elements prior to beginning the heel.

15 Fig. 3^a is a diagram of the needle row and associated devices with the instep yarn inactive following formation of split foot but tied to fabric while heel is knit with main yarn.

20 Fig. 4 is a diagrammatic perspective view showing the conditions when the instep yarn guide A is returned to feeding position after the heel is knit and the split fabric above the heel is to be knit.

25 Fig. 5 is a diagrammatic perspective showing the instep yarn about to be knit with the main yarn, after completion of the heel, to begin knitting of the split fabric above the heel.

30 Fig. 6 is a diagrammatic elevation showing the action of the instep yarn guide in assuming its out of work position preparatory to terminating the knitting of split fabric above the heel.

35 Fig. 7 is a diagrammatic view showing a later period in the action initiated in Fig. 6.

Fig. 8 is a diagrammatic plan view showing the instep yarn being knit in with the main yarn, preparatory to being clamped and cut to terminate split fabric above the heel.

40 Fig. 9 is a diagrammatic plan view of the instep yarn clamped and severed while circular knitting above the split fabric above heel is performed with main yarn.

45 The split foot fabric shown in Fig. 1 is knit with the main and instep yarns shown respectively in dark and light loops in said figure. The instep yarn remains in work until the heel is to be formed, whereupon the

50 following actions take place. The instep yarn is raised out of feeding position to dotted line position shown at A', Fig. 3, but remains tied to the fabric as shown in Fig. 3^a

at t. This action is performed by moving the yarn finger A radially outward from full line position a to dotted line position a' and then raising the instep yarn finger A to a position inside said row, see dotted line position shown at A', Fig. 3. This change in position from a' to a position inside the 55 needle row is due to the fact that the yarn finger A turns about a pivot 78', Fig. 8, inside the needle row. The yarn when raised as just described is controlled by a spring 60 detent 80^a and guard plate 80 and slot 80' of plate 80^b and held so as to avoid being clamped by the clamp 82 and severed by the cutter 80^b, so that as just stated, this instep 65 yarn remains tied to the fabric, at the point t, and will be allowed to float. The heel is 70 now knit with the main yarn.

When the heel pocket is finished and the split portion of the stocking above said pocket at the back of the stocking is to be knit, that is, the portion corresponding in 75 location to what is known as the high splice, together with the part above the instep, the instep yarn finger is again thrown into work and oscillating knitting continues the same as for the formation of the split foot.

80 Fig. 4 shows the position of the instep yarn finger A when it has been returned to feeding position, as just stated after the formation of the heel and with its end tied into the fabric at the end of the heel gore. 85 It will be noticed from this figure that the timing of this throwing in of the instep yarn again is such that it will pass between, say the fourth and fifth needles from the end of the row, which will knit on this stroke 90 (clockwise) and as this stroke continues, the yarn will wrap around the outside of the needle row, see Fig. 5, and here it will be noticed that this instep yarn will be knit into the fabric with the main yarn going in, 95 from the main yarn finger B. This knitting in of these two yarns jointly will take place at the right-hand stitch cam 1 of the main set, and Figs. 4 and 5 illustrate this, and Fig. 5 illustrates also that a short length or 100 bow of this instep yarn will be left at z extending from the point where the end of this yarn is tied to the fabric, to the point where it is knitted in at the fourth or fifth needle, 105 as the case may be. This bow appears, of course, on the inside of the fabric. This in-

step yarn, having been knit into the section of the split fabric above the heel, that is, that section which is knit with the main yarn from finger B, and this having been locked in place, the anti-clockwise stroke takes place and the length of yarn which is wrapped around the outside of the column of idle needles; see Fig. 5, will be taken up by the yarn take-up mechanism and thus drawn back through the feed finger A. On the next clockwise stroke this instep yarn will proceed to make that portion of the split fabric around the front of the ankle, and this will take place first at the left-hand knitting cam 15 of the front or second set of cams, and then at the right-hand cam on the next anti-clockwise stroke, and so on. While these actions are taking place, the portion above the heel will be knit by the main set of cams and the heel and toe needles at the main feed B.

It will be understood, of course, that up to this time, following the completion of the heel, and while the first clockwise stroke is taking place, as shown in Figs. 4 and 5, the front or second set of cams are inoperative.

This locking in of the instep yarn takes place substantially at the point z' as indicated in the diagram of the stocking, Fig. 2.

The auxiliary or instep yarn finger, when feeding, at all times lies just outside the needle row. The split fabric portion above the heel pocket having been knit, as just described, the instep yarn guide is lifted from its feeding position as shown in Figs. 6, 7, 8 and 9. In this lifting action, the auxiliary yarn feed finger is not given first a radial outward movement, as in the case when beginning to knit the heel, as now it is not intended to leave this yarn tied into the fabric, until it is brought into work again, but it is intended to sever and clamp it within the needle circle. It is also intended, however, to lock it into the upper edge of that portion of the split fabric which lies above the heel by knitting it in together with the main yarn and this is the action taking place in Fig. 8. In the diagram of the stocking, the shaded portions are those knit with the cotton yarn throughout the foot and above the heel, and the portion s shows the silk or other instep yarn, and the line of stitches where the instep yarn is locked into the dark portion of the split fabric, as indicated at z^2 .

In this lifting action just mentioned, the yarn finger is raised directly from its feeding position, as indicated in Figs. 6 and 7, and it will lay first over some of the beards and as the movement continues clockwise, the 60 yarn will pass in between the needles at some distance back from the traveling point where it is tied into the fabric and this stretch of yarn will lay against the outer side of the stems and under the beards and 65 will be in position to be taken by these

beards when the main stitch cam 1 is reached, Fig. 8, and knit and locked into the fabric with the main yarn, and Fig. 2 shows where this locking effect takes place, viz, at z^2 , as above stated. In performing the action the yarn extending from the raised yarn finger to the fabric lays on the outside of the needles and it will ride over the upper edge of the guide-plate 80, as shown in Fig. 6, and will be directed to the hook 81 which will catch the yarn on the inside of the needle row, and from there the yarn will extend out between the needles and along the outside of the stems of the few mentioned, see z^3 to z^4 , Fig. 8, to be knit in as above described. The continued movement in a clockwise direction will cause this yarn to be carried under a spring wire clamp 82 and then to a cutter 80^b at the edge of the notch 83 in the base plate 80^a where the yarn will be severed, but the cut end will be held under the clamp until this clamp is relieved from pressure and releases the yarn.

The instep yarn finger is pivotally mounted at 78'. It has a bifurcated base portion through the depending ends of which the pivot extends and it is pressed by a spring 84 which tends constantly to move the yarn finger to its lowered position. It is operated by a rod 84^a extending from the upstanding ear 84^b of its base portion.

When one of the main yarns is lifted out of work, it is carried beneath a clamp 85^a and a shear blade 85^b, which latter severs 100 it, and the cut end is held by the said clamp, as in Patent 1,608,194, Nov. 23, 1926, of which the present specification is a division.

This clamp and shear blade are both operated by a vertically extending rod, spring 105 pressed downwardly as at 86, and raised by a lever 86' bearing on the underside of pin 86^c operated by a rod 86''. The spring pressed plunger or rod 86, is connected by a pin 86^b with the movable shear blade 85^b 110 like in said patent which is pivoted to the standard at 87 and a second pin 86^d connects the vertically working plunger with the clamp 85^a so that both will be lifted when the plunger is raised to allow the yarn to pass beneath them, and thereupon they both fall together to sever and clamp the yarn.

In Figs. 2 and 9, I show an arm or finger 88 extending near the instep yarn guide. This will catch the yarn as it is raised out of work and assist in directing it as shown in this Fig. 8. This finger is an extension of the bearing 88' for the spring clamp 82. This bearing is carried by a lever 88'' pivoted to the post 89 as in said patent extending up from the shear and clamp plate and this lever is operated by a rod 90 to lift the bearing and thus raise the spring wire clamp 82 to release the instep yarn.

Fig. 9 shows the instep yarn severed and clamped. The end shown at y is the severed extension of the portion which is knit in with the main yarn at z^2 ; Fig. 2.

5 I claim:—

1. A split foot stocking having an instep yarn knit in with the yarn from the main feed at the end of the heel gore to be thereby locked in place, said instep yarn being continued intact in knitting split fabric at the 10 ankle portion at the top of the instep, the main yarn forming the split fabric above

the heel, said instep yarn being thereafter knit in with the main feed yarn, and then severed, substantially as described.

15

2. A split foot stocking having the instep yarn knit in with the yarn from the main feed at the end of the heel gore, and thereby locked in place, and thereafter continued intact in the split fabric ankle portion above 20 the instep, the main yarn forming the split fabric ankle portion above the heel.

In testimony whereof, I affix my signature.
GEORGE LAWSON BALLARD.
